HAIR CURLING DEVICE

Adolph D. Kutzler, Robert A. Kutzler, and
Raymond A. Kutzler, Waukegan, Ill.

Application August 26, 1950, Serial No. 181,664

6 Claims. (Cl. 132—34)

1

This invention relates to a hair curling device, and in particular to one in which the curler is mechanically rotated.

An object of this invention is to provide a new and improved means of rotating the hair curler for the purpose of winding a tress of hair thereon.

Another object is to provide a hair curler which is easily detached from the curling device after a tress of hair has been wound thereon and which when detached will not further rotate.

A further object is to provide a hair curling device which is light, compact, inexpensive and durable.

Other objects and advantages will become apparent from an examination of the drawings together with the description thereof wherein:

Figure 1 is an exploded perspective view of the winding device with a curling spindle separated therefrom, as just prior to attachment thereto.

Fig. 2 is a vertical section, taken on line 2—2 of Fig. 1, showing the curling spindle attached;

Fig. 3 is a vertical section, taken on line 3—3 of Fig. 2; and

Fig. 4 is a vertical section, taken on line 4—4 of Fig. 2.

As shown, the hair curling device of our invention makes use of a horizontally disposed frame or housing H having a hollow telescoping handle comprising an inner fixed member 10 and an outer movable member 12 depending therefrom. The handle member 10 is fixed to the housing H and the other handle member 12 is pivotally attached to the handle 10 near its upper end by a pivot pin 14. A rotatable shaft 16 is journaled for rotation within bearings at opposite ends of the housing H, the shaft ends 18 and 18a being extended outwardly therebeyond. A lug 20 having two arms is secured fast to the shaft near one end thereof so as to rotate therewith. A drum 22 having an associated ratchet 24 is mounted freely on the shaft 16 toward its other end, and a coil spring 26, having one end secured to an ear 28 on the ratchet 24 and its other end secured to the lug 20, encircles the shaft 16 at an intermediate point. A spring pawl 30 which engages the teeth of the ratchet 24 insures that the drum 22 will turn in one direction only.

Extending upwardly from and fastened to the lower end of the handle 10 is a coil spring 32. A flexible cord 34 which attaches to the free end of the spring extends upwardly therefrom and thence around the drum 22 through several turns from whence it leads downwardly to one arm 36 of a bell crank 38 which is pivotally secured to the handle 10 by a pivot pin 40. A spring 42 normally holds the bell crank 38 in the position shown in Fig. 2 with the arm 36 against a stop 44. Just below the housing H, and extending partially outwardly through a slot in the handle 12, is a trigger 46 which is pivotally hung on the pin 14. A spring 50 presses the lower part of the

2

trigger outwardly in which position the upper trigger portion extends upwardly into the rotatable path of the arms of the lug 20, as shown in Fig. 2. The movable handle member 12 is provided with a cam face 52 on its inner face which slidingly engages the outer arm 54 of the bell crank.

Extending outwardly from opposite ends of the housing H and parallel to the shaft 16 is a guide rod 56. A hair curler, preferably made of a light plastic material and comprising a bar 58 having at one end a resilient offset split collar 60 and a spindle 62 embraced at one end by the collar 60, is mounted endwise on the exterior of the housing H with the shaft end 18 (or 18a) projecting into an axial opening 64 of corresponding size in the spindle end and the guide rod 56 snugly extending into a similar opening 66 formed in the split in the collar 60. Ears 68 and 68a are extended radially from the shaft near its ends 18 and 18a, respectively. The ears 68a (or 68) project into an oppositely disposed pair of slots 69 extending from the spindle opening 64 at its collar end, as shown in Fig. 2, to prevent rotation therebetween. When the curler is attached to the housing as above described, the guide rod 56 enlarges the split 66 slightly, and in so doing acts as a wedge therefor. This enlarges the collar 60, causing it to release its hold on the spindle 62 thus leaving it free to rotate within the collar.

In operation the device works as follows: First of all the user grasps the instrument in one hand, as when holding a pistol, and squeezes the handle members together. When the handle members are depressed toward each other, the cam face 52 on the handle member 12 presses the bell crank arm 54 inwardly to cause the arm 36 to pull the attached cord end 34 downwardly. This causes the drum 22 to rotate which in turn winds the spring 26. When the handle member 12 is released it swings outwardly away from the member 10 in response to pressure from the bell crank spring 42. The shaft spring 26 is prevented from uncoiling by the spring pawl 30 at one end and an arm of the lug 20 at its other end which, in turn, is prevented from rotating by the trigger 46. The bell crank 38 reverts to its former position (Fig. 2) which allows the cord 34 to slip back around the drum in response to pull from the spring 32.

After the handle members have been squeezed together several times the shaft spring 26 will have been wound to a sufficient tension. The user then inserts the tress of hair to be curled in the slot 70 formed in the spindle and presses the trigger 46. This releases the engaged arm of the lug 20, allowing the shaft 16 to rotate in response to pressure from the spring 26 which causes the spindle 62 to rotate and wind the tress of hair thereon. Now it is merely necessary to disengage

the curler comprising the spindle and arm by sliding it endwise away from the shaft 16 and guide 56. When free of the guide 56 the collar 60 will spring inwardly to its normal diameter, thereupon tightly embracing the spindle 62 and preventing rotation therebetween. The curler may now be left in the tress of hair in the usual manner. The bar 58 will prevent the hair from uncoiling itself much in the manner of a bobby pin. The user is now free to slip another curler 10 on the shaft 16 and repeat the operation with another tress of hair in the same manner.

It should be noted that a curler may be placed on either end of the housing H, thus facilitating use of the device in either hand. To obtain the proper direction of spindle rotation for an inside or outside curl as desired the user need only turn the instrument in his hand. It should also be noted that the ears 68 and 68a, the bracket 20, and the spindle slot 70 are in the same radial plane so that the slot 70 is always parallel to the handle at the time the user inserts a tress of hair therein.

The present embodiment is to be considered in all respects as illustrative and not restrictive, the scope of the invention being indicated by the appended claims rather than by the foregoing description, and all changes which come within the meaning and range of equivalency of the claims are therefore intended to be embraced therein.

We claim:

1. A hair curling device comprising a housing, a rotatable shaft carried thereby, spring power means in connection with said shaft for rotation thereof, a spindle removably attached to said shaft and adapted to be rotated therewith, a split resilient collar encircling the spindle, a bar secured to the collar and extending lengthwise of the spindle and substantially parallel therewith, and means on the housing adapted to enlarge the split collar whereby to allow the spindle to rotate therein only when said spindle is attached to the shaft.

2. A hair curling device comprising a handle, a shaft carried by said handle and journaled for rotation therein, a spindle removably mounted on one end of the shaft, a resilient collar having an opening on one side arranged to frictionally embrace said spindle when in its normal state, a bar attached to said collar, and means on said housing adapted to be wedgingly received in the collar opening whereby to enlarge said collar beyond its normal size sufficiently to allow said spindle to rotate therewithin.

3. A hair curling device comprising a housing, a shaft carried by said housing and having one end portion extending exteriorly thereof, mechanical means carried by said housing arranged to rotate said shaft, an elongated hair curling spindle aligned with and detachably connected to the extended portion of the shaft for rotation therewith, a resilient collar having an opening therein embracing said spindle near one of its ends, means carried by the housing projecting into the collar opening whereby to enlarge the collar beyond its normal size sufficiently to allow rotation of the spindle therewithin, and a bar fastened to the collar spaced from the spindle and substantially parallel therewith.

4. A hair curling device comprising a housing, a shaft rotatably carried by said housing and having one end extended outwardly thereof, a spindle removably seated on the outwardly extended shaft end, a split collar embracing one

end portion of said spindle, a bar attached to the collar, means fastened to the housing and extending wedgingly into the split collar whereby to expand it beyond its normal size sufficiently to allow rotation of the spindle therewithin, a hollow handle depending from the housing, and mechanical means contained within said housing and handle arranged to rotate said shaft.

5. A hair curling device comprising a frame, a shaft rotatably carried by said frame and having one end portion extended outwardly therefrom, a hair curling spindle removably seated on the extended end portion of the shaft, a collar having a split therein embracing the spindle, a bar attached to the collar, a rod fast to the frame and having one end portion extended frictionally into the split collar whereby to forcibly expand it beyond its normal size sufficiently to allow rotation of the spindle therewithin, a coil spring connected at one end to the shaft and arranged to cause rotation thereof when under tension, a handle connected to the housing and manually operated means carried by the handle arranged to rotate the opposite spring end thereby to place the spring under tension.

6. A hair curling device comprising a housing, a shaft rotatably carried by said housing and having its ends extended outwardly thereof, a spindle removably seated on one end portion of said shaft, a resilient collar having a split therein embracing one end portion of said spindle, a bar attached to the collar, a rod fast to the housing and having one end portion extended frictionally into the split collar whereby to hold it extended, 30 a hollow compressible handle depending from the housing, a bell crank lever pivotally mounted on the handle and operable thereby in response to compression thereof, a drum mounted freely on the shaft and provided with ratchet means, 35 a spring pawl carried by the handle in engagement with the ratchet means and coacting therewith to prevent the drum from rotating in one direction, a flexible cord attached at one end to the handle in its lower portion and extended upwardly and around the drum and thence downwardly to connect with the bell crank lever, a coil spring surrounding the shaft and connected thereto and to the ratchet means, and a spring actuated trigger pivotally attached to the handle and biased to swing into locking engagement 40 with the shaft to prevent rotation thereof in response to tension of its spring and, when depressed counter to the tension of its own spring, to swing away from locking engagement with the shaft for release thereof for rotative movement, 45 the whole adapted when the handle is compressed to operate the bell crank lever thereby to wind the coil spring connected to the shaft and when the trigger is depressed to free the shaft for rotation in response to tension of its spring.
